Stockbridge & Bent

UNITED STATES PATENT OFFICE.

WILLIAM NEVINS COOK, OF NEW YORK, N. Y., ASSIGNOR TO E. B. MEYROWITZ, INC.,
A CORPORATION OF NEW YORK.

GOOGLE NOSE BRIDGE.

Application filed November 22, 1926. Serial No. 149,854.

My invention relates to google constructions and particularly to adjustable nose-pieces therefor.

Goggles are of vital importance in the operation of high speed transportation, such as aeroplanes, dirigibles, racing automobiles, etc., since it has been found essential that the operator's eyes be very carefully protected against the wind stream caused by rapid passage through the air, and from flying small objects which may be encountered in the air. This protection is most conveniently provided by means of goggles having glass lenses, worn over the operator's eyes. It has been found essential, at very high speeds, such as those attained by modern aeroplanes, that an accurate, tight, comfortable, seal be made between the wearer's face and the google frames. This seal is advantageously provided by the cushion construction disclosed in my co-pending applications, Serial No. 747,168, filed November 1, 1924, and Serial No. 146,315, filed November 5, 1926, which disclose an advantageous pattern of sponge rubber cushion, adapted to attachment to the google frame, which is of different sectional size at different portions of the periphery. The larger section is adapted to fit into the hollows of the wearer's face, as, for instance, alongside his nose, where it is otherwise difficult to obtain a tight air seal, while the thinner portions form a seal between the frame and other portions of the face. This construction, as disclosed in the specifications, has been found particularly advantageous for the pilots of modern high speed aeroplanes. It has been found, however, that different users have noses of different widths, and that, therefore, the hollows into which the cushions are fitted are separated by different distances and that accordingly a pair of goggles with a rigid nosepiece will not provide the best possible fit for all wearers.

My invention provides a particularly advantageous adjustable nose-bridge for a google construction, which is particularly adapted to the adjustment of the separation of the respective google lens pieces and their attached cushions, to fit the cushions most tightly to the wearer's face. My adjustable nose-piece is particularly adapted to ready adjustment thereof, is particularly rigid

when so adjusted, is adjustable under difficult conditions, as when in the air, and is particularly rugged and durable. It further provides a nose-bridge which is stiff, and free from lost motion when set in a given adjustment, and which is also free from rotational movement during the process of adjustment.

The construction of my invention further provides hinge members between the google frames and the nose-bridge. This hinge construction allows the adjustment of the angle between the respective google frames to fit the facial angles of the wearer so that the goggles make a close fit on a face of the round, chubby, type, and an equally good fit upon a face of the so-called hatchet type, the first requiring only a very slight angle between the respective google frames and the second requiring a substantial angle. This feature further aids in the accurate fitting of the cushions to the wearer's face. It is also convenient in that it allows of a folding of the goggles into a smaller and more compact package, which is more conveniently carried when the goggles are not in use.

By this means I am enabled to construct goggles which are particularly adapted to severe service, which are readily adjustable to the needs of various users, and which are rugged and durable.

Other objects and structural details of my invention will be apparent from the following description when read in connection with the accompanying drawings, wherein:

Fig. 1 is a view in elevation of the face side of a pair of goggles showing cushions and the nose-bridge of my invention;

Fig. 2 is a plan view of the same embodiment showing the upper side of the goggles and nose-bridge;

Fig. 3 is a front view of the same embodiment showing the nose-bridge construction in section;

Fig. 4 is a view in horizontal section of the same embodiment of my adjustable nose-bridge, and

Fig. 5 is a side view of the respective parts of the same embodiment, in position for assembly.

Referring to the figures, the usual google frames 1 are provided and cushions 2 attached thereto. The usual head strap 4 with

suitable adjusting means is likewise provided. The respective lens frames 1 are connected by a nose-piece 5.

Referring to Figs. 2, 3, 4 and 5, the nose-
5 bridge provides a pair of upright members 6 and 7 which are rotatably mounted on a vertical axis in hinge members 8 and 9, which are in turn attached to the frames 1, which may desirably be by riveting, or by
10 other convenient means. Or, alternatively, the hinge members 8 and 9 may be made as integral parts with the frames 1. The upright members 6 and 7 are fitted at the lower ends 16 and 17 to the hinge members 8 and
15 9, pass through the tubes formed in the hinge members, and are held in place by any convenient means such as by riveting the ends over washers 10 and 11.

One of the upright members, 6, of the
20 bridge-piece 5 is equipped with a holder, or clamping member, which has a socket formed within a pair of jaws or fingers 12 and 14, threaded and having tapered ends. The other upright member, 7, may be formed into
25 a cooperating bar or bit 15, adapted to be held by a friction grip in said holder or socket. The member 6 is bent at a point near the middle, to bring the holder member into a horizontal position. The other
30 upright member 7 is likewise bent at a similar point near the middle to bring its upper end 15 also into a horizontal position. The member 15 is thus adapted to enter between the jaws 12 and 14, and when so entered, the
35 lower ends 16 and 17 of the upright members 6 and 7 are positioned relatively parallel.

The end of the horizontal portion 15 may desirably be drilled and a key 18 inserted
40 therein. The key 18 is adapted to enter the slot between the jaws 12 and 14, and to aid in maintaining the parallelism and positioning of the uprights 6 and 7, and to prevent twisting between the respective goggle lenses.

A ferrule 19 is provided, knurled on the outside, with an internal thread matching the threads upon the jaws 12 and 14, and with a contracting cone 20 at one end, adapted to cooperate with the tapered ends of the jaws 12 and 14 to close them together, and thereby to grip the portion 15 of the upright member 7.

The various portions of my device may be
55 assembled in any convenient order, except that it is desirable that the ferrule 19 be passed over the member 15 before the key 18 is inserted in the hole. It is desirable that the key 18 be of such length that it will just
60 pass within the thread portion of the ferrule 19, but will not pass through the constricting cone portion 20 thereof. This construction prevents the complete disassembly of the nose-piece without removal of the ferrule 19 by complete unscrewing from the threads
65

on the jaws 12 and 14, thereby preventing accidental separation of the respective portions of the goggle.

This construction is particularly advantageous for adjustment under difficult conditions. It may happen that an aviator adjusts his goggles to his face under conditions which he thinks are satisfactory, such as those which exist on the ground. He may then ascend for a flight and find after the flight is begun, that the conditions have changed, which may be a change in temperature or in wind pressure or other features, so that the adjustment which seemed proper on the ground, no longer holds the goggles and their cushions in the most advantageous position. The construction of my invention is adapted to readjustment under such changed conditions, and it is readily possible for the aviator to readjust the goggles with one hand, which he may do by loosening the ferrule slightly and squeezing the uprights together or apart according to the needs and then retightening the ferrule. This has been found to be impossible with any other type of nose-piece construction without serious hazard to the aviator, since all other constructions require for adjustment, the use of two hands, or require the removal of the goggles from the face, as distinguished from this construction which may be adjusted in situ, by one hand, and in spite of substantial wind pressure. When so adjusted and the ferrule tightened, the construction is then firm and solid.

By the construction of my invention I have provided a goggle nose-piece which is readily adjustable, which cannot be accidentally disassembled, which may be adjusted under difficulties, which when adjusted is firm and rigid, and which is rugged and durable.

While I have shown but a single embodiment of my invention in the accompanying description, it is capable of various modifications therefrom without departing from the spirit thereof, and it is desired, therefore, that only such limitations shall be imposed thereon as are required by the prior art or indicated by the appended claims.

I claim as my invention:

1. A goggle nose-piece construction comprising tubular hinge members adapted to be attached to goggle lens frames, upright members adapted to enter said tubular hinge members, and having bends to bring portions thereof at right angles to the axis of the portion adapted to enter said tubular members, spring finger members having tapered ends, and a thread thereon, and attached to the bent portion of one of said uprights, a threaded ferrule having an internal conical end adapted to screw over said spring fingers and to displace them toward each other, and a key in the horizontal por-

- tion of another upright member, adapted to enter between said spring fingers, to pass easily within the threaded portion of said ferrule and to prevent passage of the conical portion thereof, thereover.
2. A goggle construction comprising a pair of eye-lens frames, and a nose-bridge cooperating therewith, pivotally attached thereto and comprising a friction grip chuck and bit, said chuck comprising a plurality of contractile fingers, and a conical contracting sleeve.
3. A goggle construction comprising a pair of eye-lens frames, and a nose-bridge cooperating therewith, pivotally attached thereto and comprising a friction grip chuck and bit, said chuck comprising a plurality of contractile fingers having slots therebetween, and a threaded sleeve adapted to pass thereover and having a conical end for the contraction of said fingers, said bit having a key member, adapted to cooperate with said slots for the prevention of relative rotation of said bit and fingers, said key being adapted to engage the conical end of said sleeve to prevent the withdrawal of said bit therefrom, whereby separation of said eye-lens frames is prevented.
4. In a goggle, a pair of lens frames and a nose-bridge comprising a pair of members respectively hinged to the respective lens frames, contractile fingers attached to one of said members, a grippable member attached to the other thereof, and a member surrounding said fingers to cause them to contract and grip the grippable member.
5. In a goggle, a nose-bridge comprising a member having a contractile holder, a cooperating member slidable therein, a key to prevent relative rotation of said members, and means for causing said holder to contract to frictionally engage said slidable member.
6. A goggle comprising lens frames, a pair of nose-bridge members hinged thereto and having horizontal portions in telescopic engagement, one of said engaging portions being contractile, and means for contracting said engaging portion.
7. A goggle comprising a pair of lens frames, and a nose-bridge pivotally attached thereto and comprising a friction grip chuck and bit, said chuck comprising a plurality of exteriorly threaded contractile fingers separated by slots and a sleeve engaging the thread of said fingers and having an internal conical surface for the contracting of said fingers, said bit having a key member in engagement with said slots to prevent relative rotation of said bit and fingers.
8. A goggle comprising lens frames, a pair of nose-bridge members hinged thereto, one of said members comprising contractile fingers and the other member comprising a bit within said fingers, and means for causing said fingers to contract and grip said bit.
9. In a goggle, a nose-bridge comprising a member having a contractile holder, a cooperating member within the same, a key to prevent relative rotation of said members, and means for contracting said holder into frictional engagement with said member.
10. In a goggle, a pair of lens frames and a nose-bridge pivotally attached thereto and comprising an exteriorly threaded contractile holder having a socket and a conical surface, a member slidable within said socket, and an interiorly threaded sleeve having an internal surface so situated as to engage said conical surface to contract the holder into frictional engagement with said slidable member.

In witness whereof, I hereunto subscribe my signature.

WILLIAM NEVINS COOK.
